Primary Examiner — Deanna L Pratt*Assistant Examiner* — Katie Mroczka(74) *Attorney, Agent, or Firm* — Dale Bjorkman; Rachel Kahler; Diederiks & Whitelaw, PLC(57) **CLAIM**

The ornamental design for a shaped tortilla, as shown and described.

DESCRIPTION

FIG. 1 is a perspective view of the shaped tortilla;
 FIG. 2 is an end view of the shaped tortilla of FIG. 1;
 FIG. 3 is a side view of the shaped tortilla of FIG. 1;
 FIG. 4 is a cross-sectional view of the shaped tortilla of FIG. 1, taken along line 4-4 in FIG. 2;
 FIG. 5 is a top view of the shaped tortilla of FIG. 1; and,
 FIG. 6 is a bottom view of the shaped tortilla of FIG. 1.

1 Claim, 3 Drawing Sheets(56)
